UNITED STATES PATENT OFFICE.

EDGAR S. KENNEDY, OF BALTIMORE, MARYLAND.

VENEERING-MACHINE.

SPECIFICATION forming part of Letters Patent No. 665,015, dated January 1, 1901.

Application filed December 6, 1899. Serial No. 739,381. (No model.)

To all whom it may concern:

Be it known that I, EDGAR S. KENNEDY, a resident of Baltimore, Maryland, have invented a new and useful Improvement in Veneering-Machines, which invention is fully set forth in the following specification.

My invention relates to the art of veneering, and more particularly to means whereby veneering upon cylindrical surfaces may be firmly and evenly held in contact with such surface until the glue has thoroughly dried.

The object of my invention is to firmly, evenly, and cheaply retain the veneer in contact with cylindrical surfaces—such as columns for mantels, sideboards, and the like—while the glue is drying; and with this end in view the invention resides in a machine composed, essentially, of three sets of devices—viz., winding mechanism, whereby a suitable cord, tape, or wire may be wound around the freshly-veneered cylinder; tension devices, whereby the cord, tape, or wire may be kept under an even tension while being wound, and shifting devices, whereby the winding and tension devices are caused to act progressively from one end of the cylinder to the other.

My inventive idea may receive various mechanical expressions, and I have for the purpose of illustration shown one such in the accompanying drawings; but it is to be clearly understood that such drawings are intended for the purpose of illustration only and not as defining the limits of my invention.

In said drawings, Figure 1 is a front elevation of my veneer-wrapping machine, and Fig. 2 is a transverse section on the line $x-x$ of Fig. 1 looking to the left.

Referring to the drawings, A indicates the frame of the machine, on the top of which are two jaws $a a'$, mounted to turn in suitable bearings, the jaw a' having on its shaft a driving-pulley b , which is engaged by a belt B , extending to a power-shaft. (Not shown.)

C, Fig. 2, is a column or other cylindrical surface having the veneering c thereon, said column being mounted between the chuck-jaws $a a'$, as shown in Fig. 1, so as to turn therewith.

Secured to the frame A of the machine in any suitable manner is a face-plate D, while a rail D' extends along the entire front of the

machine, being supported in any suitable manner, as by base-plate D'', attached to the frame A. Mounted to travel along the rail D' and the face-plate D is the spool and tension carriage E, consisting of an upright plate E', having arms F' F'' F'', each rigidly secured thereto and extending on opposite sides thereof and each provided with rollers, those on the arm F' bearing against the face-plate D, near the top thereof, those on the arm F'' bearing on the top of the rail D', and those on the arm F'' (shown in dotted lines in Fig. 1) bearing against the inner face of said rail, as will be understood from an inspection of Fig. 2.

G is a screw mounted in suitable bearings on the front of the face-plate D and connected by sprocket-chain H to an extension of the shaft of the chuck-jaw a' , so that the chuck-jaws $a a'$, with their supported column C, revolve with the said screw G.

Referring to Fig. 2, I is a lever pivoted to the frame-plate E' of the carriage and having a half-nut I' on the end thereof engaging the screw G, a spring I'' serving to hold the nut and screw in engagement.

I'' is a wire or cord attached to the end of the lever I opposite the nut I', by means of which the lever may be conveniently operated against the tension of the spring I'' to disengage the nut from the screw, $i i'$ being pins or hooks entering an eye or loop in the wire I'', whereby it may be retained in either position desired. When the nut I' is in engagement with the screw G and the latter is revolved, the carriage will be advanced across the front of the machine, while by lifting the link or wire I'' and hanging it by its eye or loop on the hook i' the nut I' will be thrown out of engagement with the screw G and the carriage will stop.

Revolubly mounted on a spindle extending from the face of the frame-plate E' is a spool K, having a cord wound thereon, which cord extends from the spool over an idler L to a tension device M and thence around a veneered column C. The tension device in the instance shown in the drawings consists of a bell-crank lever N, pivoted to the plate E', preferably on the opposite side thereof from the spool K, and having one arm—as, for example, the horizontal arm n —of the lever N

engaged by a spring N' , whose tension on the arm n is exerted in a downward direction, while the other arm n' of said bell-crank lever has a shaft or spindle N^2 extending through 5 a slot e in the plate E' and having a tension-pulley N^3 , with its attached brake device N^4 , revolvably mounted thereon. The tension-pulley has a V-shaped groove cut in its periphery, which groove is of such dimensions 10 as to bite or frictionally engage the cord passing therewith, preferably the bite or friction being so great as to prevent the slipping of the cord through the groove except under very great strain. The brake device N^4 is 15 rigidly connected with the tension-pulley N^3 and revolves therewith on the spindle or shaft N^2 . This brake device consists of a band-wheel N^5 , around which is passed a friction-band n^2 , preferably of leather, having one end 20 connected to a pin n^3 on the frame-plate E' and the other end connected to a spring n^4 , which is also connected to the frame-plate E' and preferably by the pin n^3 , to which the end 25 of the friction-band N^2 is connected.

25 The operation of my improved veneering-machine is as follows: The veneering c having been applied to the column C with a suitable cement between them, the column is placed in the chuck-jaws a a' , as shown in 30 Fig. 1, and the cord k is passed over the idler L , then around the tension-pulley N^3 , and thence to the column C , to which the end of the cord is attached. The machine being then 35 started, the column is revolved, and through the sprocket-chain connection the screw G is simultaneously revolved, the nut I' being in operative relation therewith. The result of 40 the revolution to the column C is that the cord k is wound thereon, and the action of the screw G upon the nut I' causes the carriage to gradually travel from left to right as 45 the winding action takes place. As here shown, the cord is wound upon the column with each coil thereof in contact with the preceding coil; but, if preferred, the feed of the carriage may be so regulated as to separate the coils or spirals of the cord to such a distance as may be required. This may be accomplished either by increasing the rotation 50 of the screw G relatively to the rotations of the column C or by providing a screw with a greater pitch than that shown. The bite or

friction of the tension-pulley N^3 upon the cord k is such that the pulley N^3 is revolved as the cord is fed along; but the free revolution of 55 the tension-pulley is prevented by the action of the brake-strap N^3 acting in relation with the brake-wheel N^5 , the amount of friction between the strap and the brake-wheel being determined by the tension of the spring N^4 , 60 coupled with the tension of the spring N' , the tendency of which is to so tilt the bell-crank lever N as to throw the spindle N^2 , and with it the tension-pulley and brake-wheel, away from the column C . On the other hand, the 65 spring N' yields to the pull on the cord k incident to the winding of the same upon the column C , and the result of the combined action of the spring N' , bell-crank N , with the tension-pulley N^3 , and brake N^5 is that a substantially equal tension is at all times maintained on the cord k between the tension-pulley and the column C . The winding action having proceeded until the entire length of the column is wound with the cord, the nut I' 75 is thrown out of contact with the screw G by lifting the link I^3 and hanging it on the hook, when the carriage may be returned to its original position either by hand or otherwise ready to repeat the operation upon another column. 80

Having thus described my invention, what I claim is—

In a machine of the character described, the combination of means for supporting and revolving the work to be wound, a carriage 85 mounted to travel longitudinally along said work, a spool mounted on said carriage, a tension-pulley mounted in yielding bearings upon the carriage whereby it may bodily advance or recede from the work, means acting 90 constantly to throw the tension-pulley away from the work, and a cord or tape carried upon the spool and wound upon the work which passes over said tension-pulley and acts constantly to cause the tension-pulley to 95 approach the work.

In testimony whereof I have signed this specification in the presence of two subscribing witnesses.

EDGAR S. KENNEDY.
